H. B. SOYSTER ET AL

ROTARY MUDDING CLAMP AND METHOD OF MUDDING WELLS

Filed Oct. 3, 1922

UNITED STATES PATENT OFFICE.

HALE B. SOYSTER AND HARVEY W. LEE, OF LOS ANGELES, CALIFORNIA.

ROTARY MUDDING CLAMP AND METHOD OF MUDDING WELLS.

Application filed October 3, 1922. Serial No. 592,102.

To all whom it may concern:

Be it known that we, HALE B. SOYSTER and HARVEY W. LEE, citizens of the United States, residing at Los Angeles, in the county of Los Angeles and State of California, have invented a new and useful Rotary Mudding Clamp and Method of Mudding Wells, of which the following is a specification.

10 This invention relates to a method and apparatus for mudding wells, such as oil wells.

In the construction or use of wells, particularly oil wells, frequently porous formations are encountered which it is desirable to seal before drilling or operating below, thereby preventing the migration of oil, water or gas from one formation to another. Commonly these porous formations are sealed by forcing fluid mud under pressure into the porous formation. This has hitherto been accomplished in a number of different manners but generally it is preferred to first seal the casing and string of inner pipe and subsequently pump fluid mud under pressure into the porous formation, thus clogging or sealing the formation. This method has the advantage of not requiring the removal of the drilling pipe from the casing and permits the mud to be pumped directly to the porous formation before being discharged into the well casing. By this method, however, the string of pipe has been frequently frozen or muddled into the well and could be removed, if at all, only with extreme difficulty.

We have found that by rotating the string of pipe during such a mudding operation the tendency of the pipe to freeze in the casing could be eliminated.

With the foregoing preliminary remarks, our invention will be more thoroughly understood from reference to the following description of the accompanying drawings which illustrate a preferred apparatus in which the process may be conducted.

Figure 1 is a diagrammatic view of an apparatus suitable for conducting our mudding process.

50 Fig. 2 is a vertical section of a mudding clamp.

Fig. 3 is a horizontal section on line 3—3 of Fig. 2.

Referring to Figure 1 of the drawings 55 there is shown in section the earth formation through which the well is drilled. A

porous formation is generally indicated at 1 which formation it is desired to mud. 2 indicates a customary well pit and 3 indicates the well casing. The top collar 15 of the well casing is indicated as being closed by a mudding clamp 4 which is utilized both to seal the top of the casing and permit rotation of the string of inner pipe 5 which in this case is shown terminating in a fish-tail bit 6.

The string of pipe 5 is shown passing through the customary rotary table 7 and supported at its upper end by a hook 8. 9 indicates a pipe line communicating with the said string of pipe 5 and leading to the outlet end of a pump 10. The inlet end of the pump 10 is connected to a source of fluid mud which is indicated by a mud tank 11.

33 indicates a conductor line provided with a suitable control valve 34 leading from the well casing to the mud supply.

Referring to Figs. 2 and 3 of the drawings the mudding clamp 4 is illustrated as comprising mainly a casing sealing member 12 having a central bore and a pipe supporting member 20 having a bore extending vertically through said member which member 20 is journaled in said sealing member 12. Said sealing member 12 is provided with a base 13 having two annular notches 14 in its lower face which notches 14 are adapted to fit the end collar 15 of the well casing. Two of these notches are shown enabling the same clamp to fit two different sized casings. 31 indicates suitable packing which is inserted between the collar and sealing member 12. Said member 12 is further provided with a cylindrical shell portion 16 extending upwardly from the base 13. In the bottom of said shell portion a race plate 17 is placed against the base. Said race plate is grooved as indicated at 18 to accommodate cone bearings 19 which fill said groove 18. The pipe supporting member 20 comprises a lower pipe stem portion 21 having a running fit with the base 13 of the member 12, an upper pipe stem portion 32 and an intermediate flange 22 which is adapted to loosely fit in the shell portion 16 of the member 12. Abutting the bottom of said flange is provided a race plate 23 having a cone notch 24 which fits over the cone bearings 19 and permits the member 20 to be rotatively supported on said cone bearings 19. There is thus pro-

vided a thrust bearing between the base 13 and the pipe supporting member. An annular cover plate 25 is screwed into the top of the shell portion 16 and fits over the 5 flange 22 of the member 21, thereby preventing an upward displacement of said member. 26 indicates a suitable pipe coupling connecting the string of pipe 5 with the lower stem portion 21 and 27 indicates 10 a similar coupling of the pipe to the upper stem portion.

28 indicates a packing gland which is screw-threaded into the bottom of the member 12 and forced against packing material 15 29 for sealing the inner pipe to said member. A locking nut 30 holds the gland in place.

For better understanding of the mudding clamp 4, it can be stated that all the 20 parts illustrated in Fig. 2 of the drawings are cylindrical in shape with the exception of the cone bearings 19.

In normal drilling operations the string 25 of pipe 5 is supported from the hook 8. When it is desired to mud the formation 1, all that is required is to first draw the string of drilling pipe above the rotary table 7 and place the mudding clamp 4 in the string of pipe. The string of pipe is then lowered 30 until the clamp 4 fits upon the upper collar 15 of the well casing. Said clamp 4 then supports the weight of the inner pipe 5 and is held firmly against the casing preventing a subsequent escape of mud from the top 35 of the casing. The inner pipe 5 is then rotated by the table 7 in the customary manner. The pump 10 is operated to pump fluid mud from the supply 11 through the inner pipe 5 which is discharged at the end 40 of the pipe. In the case illustrated, the mud is forced from the fish-tail bit 6 through the water flutes customarily provided. The mud fills the well and is forced outward into the porous formation 1 by application of 45 suitable pressure. Normally the pressure required in the mudding operation is around 250 pounds gauge. However, pressure as low as 150 pounds may be occasionally used. Preferably during the mudding operation 50 the valve 34 on the conductor line is partially opened to permit a circulation of the mud.

It can be seen that while the mud will necessarily fill the casing outside the inner pipe 5 the rotation of said inner pipe will eliminate the freezing or mudding of this pipe solidly into the hole.

While we have set forth a preferred apparatus and means for conducting this

mudding operation it is understood that 60 various advantages and modifications may be made therein without departing from the spirit of the invention. Our invention is of the scope set forth in the following claims:

We claim:

1. A process of mudding a porous formation below the casing of a well which comprises forcing mud through a string of pipe to said formation while rotating said pipe 70 and while maintaining the upper end of the casing sealed.

2. A mudding clamp comprising a clamp base adapted to seal a well casing, a clamp stem adapted to connect a string of pipe, 75 race plates between said base and plate and bearing cones between said race plates.

3. A process of mudding a well having a well casing and a string of pipe therein which comprises substantially closing the 80 space between the upper end of said casing and pipe, rotating said pipe and forcing mud through said inner pipe at a pressure greater than 150 pounds gauge.

4. A process of mudding a well having 85 a well casing and a string of pipe therein which comprises so sealing the top of the casing that escape of mud therefrom may be prevented and rotation of the inner pipe is permitted, rotating said pipe, forcing 90 fluid mud under pressure through said pipe, and drawing mud from the casing top.

5. A mudding clamp for sealing the space between a well casing and a string of pipe 95 therein, comprising a base member formed to rest upon the well casing and having a central vertical bore, a tubular member having a running fit with said base and an outwardly extended flange, and a thrust bearing between the flange and base adapted 100 to dependingly support said pipe string upon said base.

6. A mudding clamp for sealing the space between a well casing and string of pipe therein, comprising a base member adapted 105 to rest upon the well casing and having a vertical bore, a tubular member formed at its upper and lower ends for connection with a string of pipe and having a running fit with said base and an outwardly extending annular flange, a thrust bearing between said tubular member and base, and means for packing the tubular member to the base.

Signed at Los Angeles, California this 27th day of September 1922.

HALE B. SOYSTER.
